FUEL CONTROL MECHANISM

Walter C. Lindemann and Adolph T. Schmidt,
Milwaukee, Wis., assignors to A. J. Lindemann
& Hoverson Company, Milwaukee, Wis., a cor-
poration of Wisconsin

Application November 29, 1929
Serial No. 410,328

10 Claims. (Cl. 158—81)

The present improvements relate, in general, to stoves, lamps, lanterns, and the like which are adapted to employ fluid hydrocarbon as fuel wherein the fuel is conducted to a generator and burner for heating or lighting purposes. More particularly, the improvements are directed to a novel combination of elements for combining fuel components and supplying same at the point of use and are in the nature of an improvement on 10 our arrangement described and claimed in the co-pending application filed October 15, 1929, Serial No. 399,723.

A primary object, among others, is to provide a novel arrangement of parts for preparing fuel 15 for a vapor burner which is suitable alike for initial lighting or continuous combustion purposes. A further object is to provide means for regulating and varying the character of the fuel supplied from a tank or reservoir and insuring the necessary fuel components under various conditions.

Another object is to provide a novel control mechanism associated with a fuel reservoir having liquid fuel under air pressure wherein a fuel mixture of varying content may be formed from 25 the elements within the tank. A further object is to provide a device of the foregoing character wherein a rich or lean fuel mixture may be had at will, and one in which the air pressure for conveying the liquid fuel is not materially reduced 30 by reason of employing a portion of same in preparing a fuel mixture.

A still further object of the improvements is to provide a unitary structure embodying, among others, the features aforementioned. It is obvious 35 that a device of this character must necessarily have portions thereof exposed to the liquid and air spaces of the supply tank and that it is frequently operated in daily use. Furthermore, the mechanism may receive abuse or injury at the hands 40 of careless or indifferent operators. For these and other reasons, it is preferable to provide a composite unit which may be readily removed for cleaning, repairs or replacement. It is therefore, a further object of the improvements to provide 45 a unit of the type indicated which may be readily removed from and replaced into operative relation with the fuel tank and supply pipe to the generator without disturbing these elements. In accomplishing this object, a novel form of sealing 50 means has been provided wherein the application of the unit to operative position, concurrently provides a seal between the tank, supply pipe and removable unit, as well as a seal between these elements and the outside atmosphere.

55 Another object is to provide a removable unit

of the foregoing character in combination with a fuel tank and supply conduit wherein the unit when screwed home into operative position, will provide communication between the tank and conduit regardless of the location of the conduit 60 relative to the fuel passages of the unit.

To improve the efficiency and simplify the operation of vapor burning devices, in general, constitutes a further object of the invention. Other objects and advantages of the improve- 65 ments will be apparent upon reference to the accompanying specification and drawings in which

Fig. 1 is a sectional view of a vapor burning lamp, illustrating one embodiment of the present 70 improvements;

Fig. 2 is an enlarged sectional view of the removable unit, mounted in the wall of a fuel tank.

Referring to the drawings, the lamp L includes 75 the burner or mantle 5, the generator or vaporizer 6, fuel supply pipe or conduit 7 and fuel supply tank or reservoir 8. Filling means 9 is provided on the reservoir whereby liquid fuel may be poured into the liquid space F to the level indicated. An air pump, conventionally shown 80 at 10, is also provided for injecting air into the reservoir whereby the liquid fuel is maintained under air pressure which obtains above the liquid level in the air space A. Although the improvements have been illustrated in connection 85 with a vapor burning lamp, it is obvious that they are applicable to vapor burning devices, in general, such as lanterns, stoves and the like and are therefore not to be limited to the illustrated application.

The wall of the tank 8 is apertured to receive the collar or bushing 11 which is fixed in the illustrated position in any suitable manner. A port 12 is provided in the wall of the bushing. In the illustrated embodiment, portions of the bushing are disposed outside and inside the tank, a port 12 being provided in the wall of the inside portion in which the fuel supply conduit 7 is fixed, whereby said conduit communicates with the inner area of the bushing. While this conduit may, with other changes, be communicably connected with the outside portion of the bushing, it is apparent that in the arrangement illustrated, the conduit and connection are completely concealed from view. It is notable that 100 the bushing 11 is bored to several diameters for providing the annular shoulders 13 and 14.

The removable unit for supplying mixed fuel or only liquid fuel as desired to pipe 7 and the generator 6 is designated in general as 15. This 110

unit includes the valve body 16 whose exterior is turned to several diameters for providing annular shoulders 17 and 18. The body 16 is exteriorly screw threaded for engagement with 5 complementary threads on the interior of bushing 11. As illustrated the valve body is bored longitudinally to several diameters for providing communicating channels or ducts 19 and 20. A conical valve seat 21 is thus formed between 10 these channels and the inlet portion of channel 20 is also suitably bored to provide another valve seat 22. The exterior of the valve body 16 is provided with a groove or annular channel 23 which is in constant communication with channel 19 through the radially disposed passage 24. 15 A valve member 25 has threaded engagement with the outer end of the bore of valve body 16 and has an actuating knob or handle 26 extending through suitable packing means 27. This member 25 has a conical head 28 for seating on seat 21, so that communication between channels 20 and 19 may be controlled by advancing or retracting the valve by turning knob 26. A rod or stem 29 is fixed to valve member 25 and 20 is of smaller diameter than said member. This rod projects axially of the member for a substantial distance as seen in Fig. 2, and partakes in all movements of said valve member. A pipe or tube 30 of slightly larger diameter than rod 25 29, surrounds said rod so that an annular channel or passageway 31 is provided between the two. 30

The upper end of pipe 30 is provided with one or more notches 32 which forms an opening through the wall of the pipe from channel 31 to 35 the exterior. The opposite end of the pipe 30 carries a cap 33 which is apertured to provide a restricted inlet 34 to channel 31, the rod 29 extending through said inlet in one position of the device. A tension spring 35 has one end 40 fixed to cap 33 and the other end anchored to neck 36 of the valve body 16 so that the tube 30 is resiliently held with its notched end against the inner end of valve member 25. As illustrated more clearly in Fig. 2, a valve plug 37 is fixed 45 to pipe 30, having a conical head in alignment with valve seat 22.

The unitary structure just described may be inserted very conveniently and easily into operative position in the tank. Annular gaskets 38 are 50 provided so that when the valve body 16 is screwed into the bushing 11, they will interpose complementary shoulders on these members thereby forming a double seal between the body and bushing. It is notable that when the unit is screwed 55 home, the inlet 34 to tube 30 is disposed beneath the liquid level of the tank and adjacent the bottom thereof, while the inlet to channel 20 at the valve seat 22 is disposed in the air pressure region A of the tank. In this position of the unit, it is 60 seen that the annular channel 23 is in register with port 12 and pipe 7. Due to the provision of this channel 23, communication is always established between pipe 7 and channel 19 regardless of the position of passage 24 relative to port 12. 65 It is possible that the thickness of the gaskets 38 or other factors may cause passage 24 to be disposed out of alignment with port 12, i. e., in a position other than that illustrated in Fig. 2. As aforementioned, however, this possibility will not 70 prevent communication between these members due to the peripheral channel 23.

From the foregoing description, it will be apparent that liquid fuel may be supplied to pipe 7 from the tank through inlet 34, channel 31, notch 75 32, channel 19, passage 24, channel 23 and port

12. Likewise, air from the air pressure region of the tank may be supplied to pipe 7 through the inlet at seat 22, channel 20, channel 19, passage 24, channel 23 and port 12. Both the air and liquid passages just outlined are closed and sealed in the illustrated position by valve 28 seating at seat 21. In this position, the valve 28 bearing against the end of tube 30, is holding the said tube against the tension of spring 35 and likewise is holding valve 37 on said tube away from seat 22. 80 It is apparent that leakage of air between the valve body and bushing to pipe 7 is prevented by the gasket 38 between shoulders 13 and 17, so that the air pressure cannot be lost through leakage to the pipe. Leakage to the outside atmosphere is likewise prevented by this seal, which is supplemented by the gasket 38 between shoulders 14 and 18 at a point just beyond the tank wall. Accordingly, the efficiency of the organization has not been impaired or sacrificed in the provision 85 of a removable unit.

The operation of the assembled structure is similar to that described in the aforementioned copending application. With liquid fuel under air pressure in the reservoir, the valve 28 may be 100 opened slightly by turning knob 26. This allows liquid fuel entering tube 30 at inlet 34 to unite, with air entering channel 20 at 22, at the top of tube 30 so that a mixture of liquid fuel and air passes into channel 19 around valve member 25, 105 through passage 24, channel 23, port 12 to pipe 7 whence the mixed fuel is conducted to the burner which may be lighted instantaneously. After the generator 6 has been heated by the burner for a short interval, the valve member 25 may be further retracted whereupon the tube 30 and air valve 37 respond to this movement under the influence of spring 35. The valve 37 accordingly approaches seat 22 and when valve member 25 is opened wide, said valve 37 seats at 22 thus completely closing off the air inlet to the pipe 7. Thereupon liquid fuel only passes to the generator where it is vaporized for continued use by the burner. It is obvious that by suitable manipulation of the mechanism, a rich or lean mixture may be obtained and that both the air and liquid passing to the generator may be simultaneously controlled and regulated. The manner in which these results are accomplished is more specifically described in our copending application. 115

Should it become necessary to remove the unit 120 15 for cleaning, repairs or replacement, it is obvious that this may readily be accomplished by merely unscrewing the valve body 16 and removing it from the bushing 11. This may be performed without, in any way, disturbing the bushing or its connection with pipe 7. Subsequent insertion of the unit is likewise readily accomplished by merely screwing the valve body into the bushing. When this is done, the unit is, at once, in 125 operative position ready to perform its ascribed functions without the necessity of any further attention such as making connections with pipe 7 or sealing the joints, etc. All this is automatically accomplished when the unit is screwed home to 140 its final position.

The ease and simplicity with which the unit 145 15 may be inserted and removed cannot be overestimated. In providing a structure of this character with all its attendant advantages, it is notable that none of the advantages of a permanent or fixed installation have been sacrificed. In fact many added advantages have been derived. Aside from providing a removable member which permits the free passage of fuel to an outlet within 150

the tank, the present improvements afford the assurance that when the unit is placed in operative position in the tank, it is tightly sealed both with respect to the connection 7 as well as to the outer atmosphere.

Various modifications within the scope of the present improvements will be apparent to those skilled in the art and may be made without departing from the purview of the invention.

10 We claim:

1. In combination, a fuel supply reservoir having liquid fuel under air pressure, a fuel pipe leading from said reservoir, a carbureting structure for supplying mixed fuel and air to said pipe, said structure being removable as a unit from operative position without disturbing said reservoir or pipe.

2. In combination, a fuel supply reservoir, having liquid fuel under air pressure, a fuel pipe leading from said reservoir, a carbureting structure disposed within the reservoir for supplying mixed fuel and air to said pipe, said structure having control means operable exterior to said reservoir, said structure being removable as a unit from said reservoir without disturbing said reservoir or pipe.

3. In combination, a fuel supply reservoir having liquid fuel under air pressure, a fuel pipe leading from said reservoir, a selective control means comprising a unitary structure for supplying individual fuel or mixed fuel and air to said pipe, said means having a single actuating member operable from the exterior of said reservoir and being removable without disturbing said reservoir or pipe.

4. A removable control unit for fuel tanks adapted to regulate the flow of fuel therefrom comprising a valve body having a longitudinal bore communicating with a port in the periphery thereof, inlets for said bore spaced from one another whereby one may be located in the liquid space of a tank and another in the air space thereof, and a single valve mechanism controlling communication between said inlets and bore.

5. A fuel supply tank having a bushing disposed through a wall thereof, a fuel supply pipe communicating with said bushing, annular shoulders formed on the interior of said bushing on either side of said pipe communication, a valve body disposed in said bushing and having a longitudinal bore communicating with said pipe, said valve body having complementary annular shoulders aligned with said first named shoulders, packing means between complementary shoulders, means communicating said bore with said tank at spaced points, and means controlling the passage of fuel through said bore to said pipe.

6. A fuel tank having liquid fuel under air pressure, fuel outlet means for said tank includ-

ing a valve body having a bore communicating with the air space of the tank, a movable pipe establishing communication between said bore and the liquid space of the tank, a valve controlling said bore and pipe, spring means secured to said valve body and pipe for maintaining said pipe in contact with said valve, and a valve responsive to movements of said pipe positioned for controlling the air inlet to said bore.

7. A fuel supply device for hydrocarbon burners comprising a tank containing liquid fuel under air pressure having a space above the liquid level, a bushing disposed through a wall of said tank, a fuel supply pipe communicating with said bushing, a valve body disposed in said bushing having a longitudinal bore communicating with said air space, a peripheral channel on said body communicating with said bore and pipe, a valve controlling said bore, a conduit for admitting liquid fuel to said bore, and a valve controlling said conduit.

8. A fuel supply device for hydrocarbon burners comprising a tank containing liquid fuel under air pressure having a space above the liquid level, a bushing disposed through a wall of said tank, a fuel supply pipe communicating with said bushing, a valve body disposed in said bushing having a longitudinal bore communicating with said air space, a peripheral channel on said body communicating with said bore and pipe, a valve controlling said bore, a conduit for admitting liquid fuel to said bore, and a valve controlling said conduit and a common actuating member for simultaneously actuating both valves.

9. A fuel supply device for hydrocarbon burners comprising a tank containing liquid fuel under air pressure having a space above the liquid level, a bushing disposed through a wall of said tank, a fuel supply pipe communicating with said bushing within the tank, a valve body disposed in said bushing having a longitudinal bore communicating with said air space, a peripheral channel on said body communicating with said bore and pipe, a valve controlling said bore, a conduit for admitting liquid fuel to said bore, and a valve controlling said conduit.

10. A fuel control mechanism comprising a valve body defining a passage, a valve controlling one end of said passage, a tubular member extending through said passage and engaging said valve, a second valve controlling the other end of said passage and mounted on said tubular member, spring means secured to said valve body and to the lower end of said tubular member for urging said tubular member and valve thereon in closing direction and a manual actuating member for said first valve.
